CLAIM

The ornamental design for a sports equipment rack, as shown and described.

DESCRIPTION

FIG. 1 is a perspective view of a sports equipment rack constructed in accordance with the invention;

FIG. 2 is a right side elevation view of the rack of FIG. 1, the left side being a mirror image of the right side;

FIG. 3 is a front elevation view of the rack of FIG. 1, the back being a mirror image of the front;

FIG. 4 is a top plan view of the rack of FIG. 1; and,
FIG. 5 is a bottom plan view of the rack of FIG. 1.

The broken-line disclosure in the views is understood to be for illustrative purposes only and forms no part of the claimed design.
